UNITED STATES PATENT OFFICE.

HERBERT H. FREY, OF CHICAGO, ILLINOIS, ASSIGNOR TO EMMA L. REYNOLDS, OF CHICAGO, ILLINOIS.

SPARK-PLUG CLEANER.

1,319,577.

Specification of Letters Patent.

Patented Oct. 21, 1919.

Continuation of application Serial No. 126,292, filed October 18, 1916. This application filed March 23, 1918.
Serial No. 224,398.

To all whom it may concern:

Be it known that I, HERBERT H. FREY, a citizen of the United States, and resident of Chicago, in the county of Cook and State 5 of Illinois, have invented a certain new and useful Spark-Plug Cleaner; and I do hereby declare the following to be a full, clear, and exact description of the invention, such as will enable others skilled in the art to 10 which it appertains to make and use the same, reference being had to the accompanying drawings and to the characters of reference marked thereon, which form a part of this specification.

15 My invention relates to spark plug cleaners, and has for its object the provision of means for effectively and quickly cleaning the electrodes of the plug without the necessity of disassembling the spark plug 20 parts.

During the operation of a spark plug in an internal combustion engine the electrodes of the plug become covered with carbon deposits and if such deposits are not removed 25 at the required intervals a faulty operation of the engine will result. Furthermore, if the spark plug is so located in the internal combustion engine that it is subjected to lubricating oils the electrodes of the plug may 30 become coated therewith and thus fail to operate properly.

It is the primary object of this invention to clean the spark plug of such carbon and oil deposits quickly and conveniently, and 35 in accomplishing this result or object I provide a receptacle, preferably having the form of a tubular inclosure open at one end, to receive the spark plug to be cleaned. Loosely carried within the inclosure I provide 40 a plurality of impact members arranged, when this tube is shaken, to move longitudinally and strike against the electrodes of the spark plug which, after being inserted into the end of the tube, forms the 45 end wall thereof. To remove the oil deposits from the electrodes and the carbon deposits which have been loosened by the impact members the receptacle contains a suitable cleaning fluid, such, for example, as 50 gasoline which, when the tube is shaken, comes in contact with the electrodes of the plug and thus thoroughly cleans them.

These and other objects of my invention will be more clearly brought out in con-

nection with the accompanying drawings, in 55 which—

Figure 1 is a longitudinal cross-sectional view of the device of my invention showing a spark plug in position to be cleaned; Fig. 2 is a side elevational view of the spark plug 60 cleaner and the cap therefor; and Fig. 3 is a top view of Fig. 2.

This application is filed as a continuation of my prior application filed October 18, 1916, Serial Number 126,292, and similar 65 characters of reference refer to similar parts throughout the several views.

The receptacle which forms the container for the impact members and the cleaning fluid is preferably constructed of glass, as 70 shown at 4. The upper or open end of the tube 4 is flared outwardly at 5 to receive a resilient collar 6 made of cork or some composition of rubber. The resiliency of the member 6 makes it possible to insert practically any size spark plug, as illustrated in Fig. 1, so that the electrodes thereof are subjected to whatever action takes place within the tube 4. 75

Loosely contained within the tube 4 so as 80 to have longitudinal movement relatively to the tube is a plurality of impact members 7, which, in the preferred form of my invention, take the form of steel needles having substantially the same width and length, 85 as illustrated, and provided with square cut ends.

In cleaning a spark plug the cap 8 is removed from the tube and a suitable cleaning fluid 9, preferably gasoline, poured into 90 the tube to substantially the depth indicated. The spark plug to be cleaned is then screw-threaded into the resilient collar 6 and the tube 4 shaken longitudinally. The longitudinal reciprocation of the tube 4 will 95 splash the fluid 9 against the electrodes and cause the impact needles 7 to impinge against the electrodes and all portions of the spark plug which communicate with or face the inside of the tube. The needles 7 are 100 made relatively thin and long so that although they have the weight to successfully loosen the carbon deposits they are enabled to reach all portions of the spark plug, as indicated by the dotted line 10, from which 105 the carbon is to be removed. After the spark plug is cleaned it is removed from the tube 4 and the cap 8 placed over the open

end of the tube, as illustrated in Fig. 2. If the cleaning fluid or gasoline 9 is to be removed from the tube it may be poured through the opening 11 provided in the cap. 5 This opening is screened, as illustrated at 13, so that removal of the impact members is prevented during the process of discarding the cleaning fluid.

In stating that the device of my invention 10 is adapted to clean the electrodes of the spark plug I wish it to be understood that the term electrodes is to be construed broadly so as to include not only the electrodes *per se* between which the spark is 15 ranged to pass, but also those parts positioned adjacent the electrodes which, when covered with carbon deposits, prevent the proper operation of the plug.

I wish it understood that my invention is 20 not limited to any specific construction, arrangement or form of the parts, as it is capable of numerous modifications without departing from the spirit of the claims.

Having thus described my invention, 25 what I claim as new, and desire to secure by Letters Patent, is—

1. A spark plug cleaning device, comprising a tube having one end open for the reception and carrying of a spark plug, with 30 its electrode end exposed to the interior of the tube, and a plurality of needles loosely contained within the tube and adapted, when the tube and attached spark plug are shaken, to strike against the exposed end of the spark plug to remove carbon deposits therefrom.

2. A spark plug cleaning device, comprising a fluid container having one end open for the reception and carrying of a spark 40 plug, with the electrode end of the spark plug exposed to the interior of the container, and a plurality of metallic needles loosely disposed within the container and adapted, when the container and attached 45 spark plug are shaken, to strike at their

ends against the exposed end of the spark plug and coöperate with a liquid in the container to clean carbon deposits from the plug.

3. A spark plug cleaner, comprising a 50 tube open at one end, a resilient collar disposed in the open end of the tube and adapted to receive and coöperate with the tube to carry a spark plug, with its electrode end exposed to the interior of the tube, and 55 a plurality of impact needles loosely contained within the tube and adapted, when the tube and attached spark plug are shaken, to strike against the exposed end of the spark plug to clean carbon deposits therefrom.

4. A spark plug cleaner, comprising a cylindrical cleaning fluid container, into the neck of which a spark plug may be closely fitted, with its electrode end exposed to the 65 interior of the container, and a plurality of long slender wires having square cut ends disposed within the container, the length of the wires being greater than the inside diameter of the container, said wires serving 70 to remove carbon deposits from the exposed spark plug end when the container and attached plug are shaken.

5. A spark plug cleaner, comprising a cylindrical fluid container having one end 75 open and enlarged to form an internal shoulder and adapted to receive the threaded portion of a spark plug, with the inner wall of its shell substantially in longitudinal register with the inner wall of the 80 container, a gasket on said shoulder, a plurality of impact needles disposed in said container and adapted, when the container and attached spark plug are shaken, to be driven endwise against the exposed end of 85 the plug to remove carbon deposits therefrom.

In testimony whereof, I have hereunto signed my name to this specification.

HERBERT H. FREY.
